(57) **CLAIM**

The ornamental design for a golf club shaft-attachable air-resistance device, as shown and described.

DESCRIPTION

FIG. 1. is a frontal lower end isometric view of an air-resistance device adapted for attachment to either a right or a left-handed golf club shaft, the upper opposite end being a mirror image thereof;

FIG. 2 is a side view of the air-resistance device looking angularly and upwardly from the far side of FIG. 1.

FIG. 3 is a side view looking of the air-resistance device looking angularly and downwardly toward FIG. 1; and,

FIG. 4 is a side view looking toward FIG. 2 from the right side thereof.
